AUTOMATIC PUNCH PRESS STOPPING
MECHANISM

Raymond J. Zajie, Chicago, Ill.

Application May 17, 1951, Serial No. 226,770

1 Claim. (Cl. 113—38)

1

This invention relates to an automatic punch press stopping mechanism and is particularly concerned with an improved, hydraulically operated mechanism for automatically stopping the punch press immediately upon the jamming or misfeeding of the metal going through the die of the press.

In machines of the character herewith concerned, strips of material are inserted, individually, into a feedway provided in the machine and thereafter fed to the dies of the press where successive portions thereof may be worked upon with successive reciprocation of the press for stamping pieces therefrom. Said machines are adapted to be operated a stroke at a time or, if desired, the starting mechanism thereof may be depressed continuously thereby providing continuous operation of the machine at relatively high speeds. Occasionally, more than one strip of material is fed into the feedway or the dies whereupon it becomes necessary to stop the press and remove the extra strip of material. At other times a strip of material may buckle in the die or otherwise be warped or displaced whereby to jam inside the die. Unless the machine is stopped immediately before the next succeeding stroke thereof, great harm may occur to the press or valuable material may be wasted. It will be apparent that with the punch press operating at high speeds the occurrence of a jam or misfeed inside the die must be noted and corrected immediately so as to prevent such damage to the press and the wasting of expensive material, especially where the press is left unattended for substantial periods.

Accordingly, it is the principal object of this invention to provide automatic punch press stopping mechanism of the character described for stopping a press in the event of jamming or misfeeding of material inside the die upon one complete stroke of the press.

Another object of this invention is to provide an improved, hydraulically operated mechanism for automatically stopping a punch press in the event material becomes jammed or is misfed in the die thereof, which mechanism is adapted for use either with manually operable or electrically actuated stopping and starting means of the press.

Still another object of the invention is to provide an improved, hydraulically operated mechanism for automatically stopping a punch press in the event of jamming or misfeeding of material in the die thereof, which mechanism is fool-proof, highly reliable in operation, simple and very efficient in use.

2

With the foregoing and other objects in view which will appear as the description proceeds, the invention consists of certain novel features of construction, arrangement and a combination of parts hereinafter fully described, illustrated in the accompanying drawings, and particularly pointed out in the appended claim, it being understood that various changes in the form, proportion, size and minor details of the structure may be made without departing from the spirit or sacrificing any of the advantages of the invention.

For the purpose of facilitating an understanding of this invention, there is illustrated in the accompanying drawings a preferred embodiment thereof, from an inspection of which, when considered in connection with the following description, this invention, its mode of construction, assembly and operation, and many of its advantages should be readily understood and appreciated.

Referring to the drawings in which the same characters of reference are employed to indicate corresponding or similar parts throughout the several figures of the drawings:

Fig. 1 is a side elevational view of a punch press having my automatic punch press stopping mechanism associated therewith and having portions broken away to show certain operative details thereof.

Fig. 2 is a front elevational view of a portion of a punch press having my invention associated therewith.

Fig. 3 is a sectional view through the punch press taken along the line 3—3 of Fig. 2 and in the direction indicated and showing in detail the automatic stopping mechanism embodying the invention.

Fig. 4 is a sectional view taken along the line 4—4 of Fig. 3 and in the direction indicated.

Fig. 5 is an elevational view of electrical starting and stopping means for a punch press and showing the manner in which the automatic stopping mechanism embodying my invention may be associated therewith.

The punch press to which the invention is applied is designated generally by the reference character 10 and may be of any suitable size and construction. Same includes a base 11 upon which is mounted the punch press body 12 for supporting the various operating parts of the press. The press is operated in the conventional manner through a rotating driving means including a flywheel 13 connected to a crank shaft (not shown) journaled in the upper portion of the body 12. The flywheel 13 is connected to

the crank shaft through a clutch mechanism designated generally 14, the clutch 14 being of the one revolution type actuated by the rod 15. The lower end of the rod 15 is connected to a foot operated treadle 16 adapted to be actuated for starting and stopping the press. The treadle is pivotally mounted on the base 11 as at 17 and normally is biased upward by means of the spring 18 secured at one of its ends to a lug 19 on the base 11 and at its other end to the lug 20 on the treadle. In this upward position of the treadle, the punch press is stopped. The upper end 21 of the rod is joined through suitable linkages 22 to the clutch mechanism 14.

The press 10 includes stationary die stamping means 23 and movable die stamping means 24 arranged for stamping out therebetween pieces of material from strips of material fed to the punch press. The movable stamping means includes a ram 25 adapted to be reciprocated vertically along the ways or gib 26 by means of the rod 27 and the ball 28 mounted in the socket 29 in the said ram, said rod 27 being connected to the crank shaft. Secured to the face 30 of said ram is a die set 31 and secured to the face 32 of the die set is a die pad 33. As shown in Fig. 3, the die pad 33 is provided with a pair of depending punch members 34 which may be of any suitable size and form desired for performing a certain stamping operation on the material fed to the press.

The stationary stamping means 23 is mounted upon the table 35. Said means includes a base member 36, a shim 37 mounted on the base 36, a die set 38 secured on the shim, and a cap 39 secured to the shim 37. Openings 40 are provided in the cap 39 and die set 38 for receiving the depending punch members 34 upon the downward stroke of the ram 25 to perforate, for example, the strip of material 41. The lead pins 42 mounted between the base 36 and the die set 31 serve also to guide the vertical reciprocal movement of the movable die stamping means 24.

The construction of the punch press 10 herein above described is well known in the art, it being understood that the construction of the punch press 10 per se is not intended to form a part of this invention. By the same token, it is not intended to be limited thereby, but as will become apparent hereinafter the automatic punch press stopping mechanism embodying the invention is adapted to be applied to punch press machines of any suitable form, size or construction.

It will be understood that punch presses of the character herewith concerned are devised to perform successive operations upon successive portions of the metal strips fed to the press. In operation, such presses are run at continuous speeds and often are set and left to run unattended. It is necessary therefore to provide a stopping mechanism for stopping the press when any abnormal condition occurs, such as jamming or misfeeding of the metal strip in the press.

The automatic stopping mechanism constituting my invention operates to stop the reciprocating motion of the movable stamping means 24 in one complete stroke in the event material going through the die set 38 misfeeds or becomes jammed inside said die. Generally, in the event of a jam or misfeed in the die 38, when the ram 25 comes down on its downward portion of a complete stroke, there is provided a guide pin on the die set 31 which comes in contact with the jammed or misfed strip of metal in the die 38. The pin upon striking the jammed metal is caused to

move upward, the upward movement of the pin being transferred by means of cam action and a push rod to a spring action cylinder housed and secured to the die set 31. By the time the ram 25 completes its full downward stroke, the movement of the cylinder depresses a hydraulic piston. The movement of the piston is transferred hydraulically to a second piston, the movement of the second piston being adapted to engage and trip a spring loaded lever member. Movement of the lever member results in release of the foot-operated treadle 16, which in turn actuates the pull rod 15 connected to the clutch 14 for stopping the reciprocating movement of the ram 25 at the top of the stroke. It will be apparent that by means of such automatic stopping mechanism the punch press is prevented from entering upon the next succeeding stroke once the guide pin thereof comes in contact with a strip of material which is jammed or misfed in the die 38. The press 10 may then be cleared for normal operation. I also provide means for engaging the treadle 16 for keeping the treadle in a continuously depressed condition for operating the machine 10 at continuous high speed. The automatic stopping mechanism is adapted to release said means for preventing succeeding operation of the press in the event of jamming or misfeeding.

Referring now to the drawings wherein a preferred embodiment of the automatic stopping mechanism embodying the invention is shown, the die set 31 is provided with a cylindrical bore 45 adapted to be closed at its upper end by a removable plug 46. The lower end of the bore is adapted to receive therein a guide pin 48, said pin 48 being movable vertically in said bore. The pin 48 includes an elongate rod portion 49 and an enlarged diameter portion 50 seated in the bore. The portion 50 is provided with a central recess 51 and in order normally to bias the said pin downwardly as viewed in Fig. 3, there is provided a coil spring 52, said spring having one end thereof engaged against the bottom wall 54 of the recess 51 and its other end 55 engaged against the plug 46. The portion 50 is annularly shaped and includes an inclined shoulder portion 56 of a diameter less than that of the bore 45.

The shoulder portion 56 is in the nature of a cam surface and is arranged to engage the end 57 of a horizontally disposed push rod 58 housed in the horizontally disposed bore 53 provided in the die 31. The second end 59 of the rod 58 has an integrally formed boss 60 thereon, which boss 60 is disposed in the casing 61 attached to the die 31 by long screws 62. The casing 61 includes an upper wall 63, a lower wall 64 and a pair of spaced-apart vertical walls 65 and 66 to which the walls 63, 64 are secured by means of the screws 67. There is thus formed between the walls 65 and 66 a vertically extending bore 68 in which is housed for vertical movement a spring action cylinder 69. The cylinder 69 is shorter than the length of the bore 68 thereby permitting substantial vertical movement in said bore.

The cylinder 69 has a vertically extending recess 70 in the top portion thereof adapted to receive therein a coil spring 71. The spring 71 is arranged normally to bias the cylinder 69 downward, said spring having its lower end engaged against the bottom wall 73 of the said recess 70 and its other ends engaged against the inside surface of the wall 63. A pin 75 is slidably mounted in a groove 72 on the inside surface of wall 66, said pin extending into a recess 70 in cylin-

der 69 between wall 13 and wall 74. A short, slideable rod 76 has one end thereof engaged against boss 69 and its opposite end extending into the recess 79' spaced from pin 75. A spring 78 is disposed between rod 76 and 75 in said recess and is arranged normally to bias rod 76 outwardly from recess 79' against boss 69. In this normal position, rod 76 will have a portion 77 protruding from cylinder 69 which portion acts as a stop member. The portion 77 abuts the shoulder 79 on wall 65 and this position prevents cylinder 69 from moving downwardly under the bias of spring 78. Referring to Fig. 3, when rod 58 is moved to the right as guide member 48 is moved vertically, the boss 69 will move portion 77 to the right free of shoulder 79 thereby permitting spring 78 to urge the said cylinder downwardly in bore 68. The pin 75 will ride in groove 72 along with said cylinder. Upon return of the cylinder, as rod 76 passes shoulder 79, spring 78 will urge same into position engaging said shoulder.

Mounted on the table 35 by means of a suitable angle bracket 80 is a piston housing 81 having a central bore 82 in which is adapted to move a piston 83. Said bore 82 may be filled with a hydraulic fluid 84. The piston 83 is secured to the end 85 of an elongate rod 86, said rod being movable in the wall 87 of the said housing. The rod 86 in turn is secured to another rod 88, said rod 88 being attached to pin 88' secured to bottom wall 74 of cylinder 69 through wall 64. Movement of the piston 83 will exert pressure upon the hydraulic fluid 84.

Mounted within a wall of the piston housing 81 is a conventional compression coupling 89 communicating with the bore 82. An elongate tube 91 is joined to the coupling 89 at one end 91 and at its other end 92 to a T-shaped union 93. The arm 94 of said union is threaded within the wall 95 of a cylindrical casing 96 having a central bore 97 adapted to hold therein hydraulic fluid 98. A piston 99 is slidably mounted within the bore 97. A push rod 100 is secured at one end 101 thereof to said piston 99, the other end 102 of said piston being disposed within a housing 103 secured on the base 11 by means of angle brackets 104 and screws 105.

The housing 103 is provided with means for actuating the treadle 16 for stopping the press 10 in the event of jamming or misfeeding. Said housing 103 includes a pair of vertically spaced apart walls 106, 107, a top wall 108 and a bottom wall 109 suitably joined and providing a central cavity 110 therein. Disposed within the cavity 110 is an elongate push rod 111 provided at its top end 112 with a cap 113, the body of the rod being inserted through the top wall 108 and the bottom wall 109 of the housing 103. Secured on the rod 111 intermediate the ends thereof is an annular disc 114. The rod 111 has portions thereof disposed outside of the housing 103, the bottom end 115 thereof contacting the treadle 16. A coil spring 116 is mounted over the rod 111 with one end 117 engaged against the inside of the wall 109 and its other end 118 engaged against the bottom surface of the disc 114.

Mounted on the wall 106 and extending within the cavity 110 is provided a stud shaft 120. The end 121 of said shaft is pivotally secured to a plate member 122. The member 122 is provided with a hook 123 adapted to engage the top surface 124 of the disc 114 and a straight portion 125 which is disposed against the end 102 of the rod 100. The member 122 is considerably shorter 75

than the rod 111 and is arranged so that when the hook 123 is engaged with the disc 114, the spring 116 will be compressed whereby normally to urge the rod 111 upward out of contact with the treadle 16 when released. A spring 125 is secured between the wall 106 and the hook 123 whereby normally to bias the hook into engagement with the disc 124.

The operation of the automatic stopping mechanism is as follows: The operator controls the starting of the press 10 by means of the treadle 16. When the treadle 16 is depressed, the pull rod 15 is carried along therewith and through the linkages 22 causes the clutch 14 to engage the flywheel 13 for reciprocating the ram 25. Should the operator desire to run the press continuously, he may depress the cap 113 moving the rod 111 downward against the treadle 16. The hook 123 will engage the disc 114 after the rod 111 is depressed a sufficient distance whereby to prevent upward movement of the said rod out of contact with the treadle 16.

With the machine in operation the ram 25 is being reciprocated vertically at high speeds 25 carrying along therewith the guide pin 48. The material 41 being fed through the die 38 is provided with an opening 130 which is arranged to receive the portion 49 of the pin 48 on its downward stroke as shown in Fig. 3. Thus, presuming that the material 41 is being fed through the press without occurrence of any abnormal condition such as jamming or misfeeding, the stamping operation of the punch pins 34 will proceed and the guide pin 48 will enter the opening 130 30 in said material 41 without any effect. However, should the material 41 jam or misfeed thereby throwing the opening 130 out of alignment with the guide pin 48, the pin 48 will strike the material 41 on its next downward stroke. Contact 40 with the material will cause the pin 48 to be moved upward as viewed in Fig. 3, thereby putting into operation the automatic stopping mechanism to stop the press prior to its next downward stroke.

Upward movement of the pin 48 in the bore 45 will cause the shoulder 56 to ride against the end 57 moving the push rod 58 to the right a distance corresponding to the width of the shoulder 56. Movement of the rod 58 will push the rod 76 50 against the spring 78 and move portion 77 free of shoulder 79 thereby freeing the cylinder 69. The spring 78 will then bias the cylinder downward moving the pin 88', rod 88, the rod 86 and the piston 83 whereby to exert a pressure 55 on the hydraulic fluid 82. The pressure thus exerted on the fluid 82 will be translated through the tubing 90 to the hydraulic fluid 98 in the casing 96 and thence against the piston 99. The piston 99 will be moved to the left as seen in Fig. 60, pushing the end 102 thereof against portion 125 of the member 122. The member 122 will then be pivoted clockwise causing disengagement of the hook 123 from the disc 114. Upon release of the hook from the disc the spring 116 will urge the rod 111 upward out of engagement with the treadle 16. The treadle 16 will then also be urged upward by means of the spring 13 causing the pull rod 15 to be moved upward. The upward movement of the rod 15 will be translated 70 through the linkages 22 to the clutch 14 to stop the machine 10. It will be noted that the stopping of the press 10 is accomplished before the next succeeding downstroke after occurrence of a jam or misfeed in the die 38.

My stopping mechanism above described is

adapted for use with an electrical starting and stopping mechanism such as shown in Fig. 5. The tubing 92 is there shown joined to the T-shaped union 93 and the arm 94 thereof is joined to a casing 96 such as previously described. The casing 96 is supported by a bracket 131 secured on the press 10. There is shown the end 132 of a slideable member (not shown) mounted within the casing 96 and adapted to be moved hydraulically in a well-known manner. The end 132 is disposed in engagement with a push button 133 of a switch 134 connected into an electrical circuit for stopping and starting the press 10. The end 132 normally is biased away from the button 133 by means of a spring 135 mounted over the same, one end of the spring being biased against an annular shoulder 136 on the said end and the other end of the spring being biased against the switch 134. Upon the occurrence of an abnormal condition in the die 38, the upward movement of the guide pin 48 will result in the end 132 of slideable member being moved by hydraulic pressure against the push button 133 to open the switch 134 and stop the press. Again, the automatic stopping action of my mechanism may be accomplished before the next succeeding stroke of the ram 25.

It is believed that this invention, its mode of construction and assembly, and many of its advantages should readily be understood from the foregoing without further description, and it should be manifest that while a preferred embodiment of the invention has been shown and described for illustrative purposes, the structural details are nevertheless capable of wide variation within the purview of the invention as defined in the appended claim.

What is claimed and desired to be secured by Letters Patent of the United States is:

In a punch press of the character described and having a reciprocating die head, a stationary die bed, a conventional driving and re-cycling mechanism for said press, said press having a

continuous strip of metal passing over said bed for operation of the die head on successive portions thereof with successive reciprocations of the die head, a control mechanism including a spring biased treadle member connected to said driving mechanism for operating same and being continually urged to a press stop position, a push rod arranged to move the treadle to a position causing operation of the driving mechanism and means thereafter locking the push rod in a position resulting in re-cycling of the press, an automatic stopping mechanism for stopping the press in the event said strip becomes misaligned relative to the die head comprising a movable guide member housed in said die head, spring-action means adapted to be mounted on the head in operative association with said guide member and a hydraulic fluid system connected between said spring-action means and treadle locking means, said spring-action means adapted to actuate the hydraulic system to release the treadle locking means to permit movement of the treadle to press stop position and comprising a casing adapted to be secured to said die head, a spring-biased cylinder movably disposed in the casing and operatively connected with said system, a movable stop member adapted to maintain the cylinder immovable against the bias of said spring, said stop member being operatively connected with said guide member and arranged to be moved thereby free of the cylinder whereby said cylinder may be biased to move causing a pressure to be exerted through said hydraulic system for stopping the press.
